United States Patent

Des. 238,632

Patented Feb. 3, 1976

238,632

DISPLAY STAND

Gary Wilding, Chicago, Ill., assignor to Richton International Corporation, New York, N.Y.

Filed May 13, 1974, Ser. No. 469,334

Term of patent 14 years

Int. Cl. D20—02

U.S. Cl. D6—23

FIG. 1

FIG. 2

FIG. 3

FIG. 1 is a front elevational view of a display stand embodying my new design, the display stand having the same appearance from all sides;

FIG. 2 is a top plan view thereof; and

FIG. 3 is a bottom plan view thereof.

I claim:

The ornamental design for a display stand, substantially as shown and described.
